UNITED STATES PATENT OFFICE.

ROBERT BENNETT HUTCHESON, OF MONTREAL, QUEBEC, CANADA.

WHIST-COUNTER.

1,032,606.

Specification of Letters Patent. Patented July 16, 1912.

Application filed June 6, 1910. Serial No. 565,277.

To all whom it may concern:

Be it known that I, ROBERT BENNETT HUTCHESON, of the city of Montreal, in the Province of Quebec, Canada, have invented 5 certain new and useful Improvements in Whist-Counters; and I do hereby declare that the following is a full, clear, and exact description of the same.

My invention has for its object to provide 10 means for indicating the honors held, in a hand of whist to enable them to be readily ascertained at a glance.

The invention may be said to consist of the combination and arrangement of parts 15 hereinafter described and pointed out in the claims.

For full comprehension, however of my invention reference must be had to the accompanying drawings forming a part of 20 this specification, in which similar reference characters indicate the same parts and wherein—

Figure 1 is a perspective view of my improved game counter in use; Fig. 2 is a side 25 elevation of the counter; Figs. 3 and 4 are respectively end and plan views of the same; and Fig. 5 is an enlarged detail sectional view taken on line A A Fig. 3.

This invention comprises a resilient clip in 30 the form of an open ring *b* of steel, bone, or other suitable material of a width and circumference to fit comfortably on the thumb or knuckle of a card player, preferably the thumb of his left hand if he is right handed, 35 as by such arrangement the counter is more conveniently manipulated and less liable to be disturbed when the player deals.

Attached to the side of the clip by solder or other means, is a plate *c* having thereon 40 five or any desired number of hinged fingers *d* with disks *e* at their outer ends such fingers being arranged in a row longitudinal of the plate. This plate may be metal or other material. These fingers are independently 45 hinged in order that either one may be moved without disturbing the others, and the hinge connections preferably consist of a hinge-pin *g* fixed in bearings *h* fastened to the plate and the ends of the fingers being 50 bent back upon themselves to form loops *k* inclosing and in pivotal relation with the pin; while a spring consisting of a bent plate *m*

secured at one side to the plate *c* by solder as at *n* or any other preferred means, extends between the said bearings and beneath 55 the looped ends of the fingers *d*, upon which latter it bears, thus causing sufficient friction between them and the hinge rod to hold the fingers yielding in vertical or horizontal positions as required. The disks *e* are made 60 of, preferably, the same material as the fingers and secured to the outer ends thereof by solder or any other suitable means or may be made in one piece therewith. Marked on the faces of these disks are the 65 symbols A, K, Q, J, and X representing the ace, king, queen, jack, and ten spot of a pack of cards. The hinge-pin *g* is cut away at intervals along its length to form shoulders 70 *i* against which the looped ends *b* of the fingers *d* bear, thus preventing the lateral displacement of the fingers.

When the player discards an honor he turns down the disk bearing the symbol representing such honor so that at the end of 75 the hand it can be readily ascertained to whose credit the honors are to be scored. The score is apparent owing to the fact that the disks, when pulled down lie face upward, displaying their respective symbols. 80

Although I have described my invention as relating to the game of whist it may be advantageously applied to other games without departing from the spirit of my invention, and may also be used as an advertising 85 medium, the advertisement being placed on the ring or elsewhere.

What I claim is as follows:—

1. A game counter consisting of a ring adapted to be worn on the thumb or finger 90 of a player; a metal plate secured to the ring; a hinge pin carried by the plate and cut away at intervals to form shoulders; a series of fingers rotatively mounted upon the cut away portions of the hinge pin; disks 95 carried by the fingers; and a bow spring bearing between the plate and the hinged ends of the fingers to hold the latter yielding in any desired position.

2. A game counter consisting of a ring 100 adapted to be worn on the thumb or finger of a player; a metal plate secured to the ring; a hinge pin carried by the plate and cut away at intervals to form shoulders; a

series of fingers rotatively mounted upon the cut away portions of the hinge pin; disks carried by the fingers; and a bow spring bearing at its ends upon the plate and having its intermediate portion bearing yieldingly against and curved to fit the hinged ends of the said fingers.

In testimony whereof, I have signed my name to this specification, in the presence of two subscribing witnesses.

ROBERT BENNETT HUTCHESON.
